UNITED STATES PATENT OFFICE.

JOHN F. TOOMEY, OF NEW YORK, N. Y., ASSIGNOR TO AMERICAN TELEPHONE AND TELEGRAPH COMPANY, A CORPORATION OF NEW YORK.

RINGING REGULATOR.

1,408,784.

Specification of Letters Patent. Patented Mar. 7, 1922.

Application filed September 17, 1918. Serial No. 254,493.

To all whom it may concern:

Be it known that I, JOHN F. TOOMEY, residing at New York, in the county of New York and State of New York, have invented 5 certain Improvements in Ringing Regulators, of which the following is a specification.

This invention relates to ringing arrangements and particularly to arrangements for 10 transmitting ringing current over transmission lines.

It has been found desirable, when ringing over certain types of lines, to have the ringing continue for a certain interval of time.

15 A desirable interval for long distance lines has been found a practice to be approximately two seconds, although the interval may vary under different conditions. In former arrangements for ringing over long 20 distance lines the ringing would only continue during the interval in which the operator held closed the ringing key. With such arrangements it has been found difficult to obtain a ringing interval which would be of 25 satisfactory or uniform duration. Accordingly it is one of the objects of this invention to provide a means which will operate, when the ringing key is thrown, to insure the continuation of the ringing for a satisfactory and uniform interval of time. Other 30 and further objects of this invention will be clear from the detailed description to be given later.

The ringing arrangements of this invention 35 may be associated with either a cord circuit, a section of a transmission line which is composed for both telephone and telegraph service, or a section of a transmission line which is not so composed. There is 40 associated with the cord circuit or transmission line means which respond whenever the ringing key of the cord circuit is thrown or whenever a ringing impulse is transmitted over the line. Controlled initially by 45 these responsive means is a chain or series of slow releasing relays and means whereby ringing current is applied to the cord circuit or transmission line. When the ringing key of the cord circuit is released or when the 50 operator ceases to transmit ringing current over the transmission line and these responsive means are released, the means for applying ringing current to the cord circuit or transmission line will remain held operative 55 by the chain or series of slow releasing re-

lays during that interval which elapses while the chain or series of slow releasing relays are releasing. By increasing or decreasing the number of slow releasing relays in this chain the ringing interval may be prolonged 60 or shortened as desired.

In Fig. 1, the arrangements of the invention are illustrated as adapted for use with the ringing apparatus of a line composited for both telephone and telegraph service. 65 In Fig. 2 is illustrated a modification of the invention showing the arrangements as associated directly with a section of a transmission line.

In the Fig. 1 is illustrated a composited 70 transmission line, the section L_1 of which terminates at switchboard apparatus and the section L_2 of which extends to a distant station. The sections L_1 and L_2 are interconnected by the repeating coil 47. Associated with the repeating coil 47 are the relays 48 and 49, the relay 48 being adapted to respond to the type of ringing current generated at the switchboard apparatus and which in practice may have a frequency 80 of 16 cycles. The relay 49 is adapted to respond to the type of ringing current coming in over the section L_2 which in practice may be of a frequency in the neighborhood of 133 cycles. Under the control of 85 relay 48 is the relay 412 which in turn controls the operation of a series of slow releasing relays such as the relays 413 and 414. The relay 412 initially controls relays 46 and 411, which are in turn held operative by the relays 413 and 414. The relay 46 serves to connect the section L_2 of the line to the interrupter apparatus 415. The relay 411 serves to start the interrupter apparatus 415 into operation. The interrupter 90 apparatus 415 serves to translate current from a local source into current having a frequency suitable for transmission over the section L_2 of the line and which in practice might be in the neighborhood of 133 cycles. 100 Under the control of relay 49 is the relay 410 which in turn controls the relay 45. The relay 45 serves to connect to the section L_1 of the line a source of ringing current suitable for operating the ringing apparatus at the switchboard, which in practice 105 might have a frequency in the neighborhood of 16 cycles.

The operation of the arrangements illustrated in Fig. 1 is as follows: When the 110

operator at the central office or switchboard at which the section L_1 of the line terminates starts her ringing apparatus into operation by depressing the key, or otherwise, ringing current will be transmitted over the sides of section L_1 and over conductors 41 and 42, through the left hand windings of repeating coil 47 and through the winding of relay 48. As the relay 48 is adapted to respond to 5 ringing currents suitable for use over section L_1 it will be energized. The relay 49, however, is not adapted to respond to currents of this type, and will not be energized. The operation of relay 48 will close the following circuit: from ground, contact 422, conductor 423, armature and contact of relay 48, conductor 424, windings of relay 412 to battery and ground. The closing of this circuit will energize relay 412 which, by 10 pulling up its left hand armature, will close the following locking circuit: from ground, contact 427, conductor 426, lefthand armature of relay 412, contact 425, winding of relay 412, to battery and ground. The energization of relay 412 also closed the following circuit: from ground, armature of relay 412, contact 428, conductor 429 to connecting point 435. At this point the current will divide, one portion thereof being 15 transmitted over conductor 436 and the winding of relay 46 to battery and ground. The other portion of the current will be transmitted from connecting point 435 over conductor 433, winding of relay 411, to battery and ground. The closing of these circuits will energize the relays 46 and 411. The energization of relay 46 disconnects the sides of section L_2 of the line from the conductors 43 and 44 and connects the sides 20 of section L_2 to the conductors 431 and 432 leading to the right-hand winding of transformer 438 of the interrupter apparatus 415. The energization of relay 411 causes the interrupter apparatus to function by 25 completing the following circuit: from ground, lower armature and contact of relay 411, conductors 434 and 437, contact and armature of relay 441, winding of relay 441, lefthand winding of transformer 438, conductors 439 and 440 to source 416. Current from the source 416 will now be transmitted over this last mentioned circuit and will be translated by the interrupter apparatus 415 into current having a frequency 30 suitable for transmission over the section L_2 of the line, which in practice may be of a frequency in the neighborhood of 133 cycles. This current will be transmitted through transformer 438 and over conductors 431 and 432 to the sides of the line L_2 . The energization of relay 411, by pulling up its upper armature, will close the following circuit: from ground, upper armature and contact of relay 411, conductor 419, winding of relay 410, the battery and 35 ground. The closing of this circuit will maintain the relay 410 in an energized condition and thereby prevent relay 45 which is under its control from operating simultaneously with the relay 46. Upon the before-mentioned energization of relay 412, the following circuit will be closed: from ground, armature of relay 412, contact 442, winding of relay 413, to battery and ground. The closing of this circuit will energize the relay 413 which will pull up its armature and close the following circuit: from ground, armature of relay 413, contact 443, winding of relay 414, to battery and ground. The closing of this circuit will energize the relay 414 which will pull up its armature and connect a ground to conductor 430 and the circuits formerly closed through relays 46 and 411. The energization of relay 414 will at the same time open at contact point 427 the locking circuit formerly closed through the relay 412, thereby releasing the relay 412. The deenergization of relay 412 will open the circuit formerly closed through relays 46 and 411 at contact point 428 and the circuit through relays 46 and 411 will now be completed over conductor 430 and armature and contact of relay 414 as formerly pointed out. The deenergization of relay 412 will also open at contact point 442 the circuit closed through the relay 413. As the relay 413 is a slow releasing relay it will hold up its armature momentarily and will then release and will open at contact point 443 the circuit closed through the relay 414. As the relay 414 is a slow releasing relay, it will hold up its armature momentarily and upon releasing will open the circuit formerly closed over conductor 430 about the relays 46 and 411, thereby deenergizing relays 46 and 411 and causing the transmission of ringing current out over the section L_2 of the line to cease. It will be seen that after the operator at the switchboard with which the section L_1 of the line is connected ceases to ring and the relays 48 and 412 are deenergized, ringing current will still be transmitted out over the section L_2 of the line during the interval which elapses while the slow releasing relays 413 and 414 are releasing. By adding to the circuit additional slow releasing relays similar to the relays 413 and 414, this ringing interval may be prolonged if desired. The ringing current coming in over the section L_2 of the line will be transmitted over conductors 43 and 44 through the right hand windings of repeating coil 47 and through the windings of relay 49. As the relay 49 is adapted to respond to ringing current of this type, it will be energized. The relay 48 however, will not be energized, as it is not adapted to respond to currents of this type. The operation of relay 49 will open the following normally closed circuit 120 125 130

at contact point 444: from ground, armature of relay 49, contact point 444, conductors 418 and 419, winding of relay 410, to battery and ground. The opening of this 5 circuit will deenergize relay 410 which will allow its armature to retract and thereby close the following circuit: from ground, contact point 420, conductor 421, winding of relay 45, to battery and ground. The closing 10 of this circuit will energize the relay 45 which will disconnect the sides of section L_1 of the line from conductors 41 and 42, and will connect to the section L_1 of the line a local source 417 of ringing current suitable 15 for operating the ringing apparatus located at the switchboard which ringing current may in practice have a frequency in the neighborhood of 16 cycles.

In the Fig. 2 is illustrated a transmission 20 line L_3 across which is bridged a relay 51 which is adapted to respond whenever an impulse of ringing current is transmitted over the line L_3 . Under the control of relay 51 is the relay 53 which in turn controls the 25 operation of the relay 54, whereby a local source of ringing current may be connected to another section of the line L_3 over which it is desired to ring. Under the control of relay 53 is the slow releasing relay 512, 30 which in turn controls the slow releasing relay 514. The slow releasing relay 514 also serves to control the relay 54.

The operation of the arrangement illustrated in Fig. 2 is as follows: When a ringing impulse is transmitted over the line L_3 , 35 the relay 51 responds and by pulling up its armature closes the following circuit: from ground, armature and contact of relay 51, conductor 52, winding of relay 53 to battery 40 and ground. This energizes the relay 53 and closes the following locking circuit therefor; from ground, contact 57, conductor 56, armature of relay 53, contact 55, winding of relay 53, to battery and ground. 45 The energization of relay 53 also serves to close the following circuit. From ground, armature of relay 53, contact 58, conductors 59 and 520, winding of relay 54 to battery and ground. The closing of this circuit 50 energizes the relay 54 which connects a section of the transmission line over which it is desired to ring to a local source of ringing current 521. Ringing current from the source 521 will be transmitted out over the 55 line as long as the relay 54 is maintained in an energized condition. The energization of relay 53 also closes the following circuit: from ground, armature of relay 53, contact 510, conductor 511, winding of relay 512, to battery and ground. The energization 60 of relay 512 closes the following circuit: from ground, armature and contact of relay 512, conductor 513, winding of relay 514, to battery and ground. The energization 65 of relay 514 serves to open at contact point 57 the locked circuit formerly closed through the relay 53, thereby deenergizing the relay 33. The energization of relay 514, however, serves to apply a ground to conductor 515 and thence to conductor 70 520, thereby maintaining the circuit through the relay 54. On the deenergization of relay 53 the circuit formerly closed through relay 54 is now broken at contact point 58 and the circuit through relay 54 is completed over 75 conductor 515 and contact 516 as formerly pointed out; and the circuit formerly closed through the relay 512 is now broken at contact point 510. The breaking of this last mentioned circuit deenergizes the relay 512. 80 As the relay 512 is a slow releasing relay it will momentarily hold up its armature and then release and open the circuit formerly closed through the relay 514, thereby deenergizing relay 514. As the relay 514 is also 85 a slow releasing relay, it will momentarily hold up its armature and will then release and will open at contact point 516 the circuit formerly closed through the relay 54, thereby releasing the relay 54 and causing 90 the transmission of ringing current over the line to cease. It will be seen that the relay 54 will be energized and ringing current will be transmitted over the line during that 95 interval, after the cessation of the original ringing impulse, which elapses while the slow releasing relays 512 and 514 are releasing. By increasing or decreasing the number of slow releasing relays, such as the relays 512 and 514, the ringing interval may 100 be prolonged or shortened, as desired.

While the invention has been disclosed as embodied in certain specific arrangements which are deemed desirable, it will be understood that it is capable of embodiment in 105 many and widely varied forms without departing from the spirit of the invention as defined in the appended claims.

What is claimed is:

1. A transmission line, means associated therewith responsive to alternating ringing currents transmitted over one section of said line, a chain of slow releasing relays initially controlled by said responsive means and controlling each other in sequence, means controlled by said chain of relays, when operated, to disassociate said chain from said responsive means, a source of ringing current, and means controlled by said chain of relays to apply current from said source to 115 another portion of said line.

2. A transmission line including two line sections, means associated with one of said line sections responsive to alternating ringing current transmitted over said line section, a chain of slow releasing relays initially controlled by said responsive means and controlling each other in sequence, means controlled by said chain of relays, when operated, to disassociate said chain 125 130

from said responsive means, a source of alternating ringing current suitable for transmission over said other line section, and means controlled by said chain of relays until all of said relays have released to apply current from said last mentioned source to said last mentioned line section.

3. A transmission line, a relay associated with one section of said line and responsive to currents suitable for transmission over said line section, a second relay associated with another section of said line and responsive to currents suitable for transmission over said line section, a source of current suitable for transmission over said first mentioned line section, a second source of current suitable for transmission over said

second mentioned line section, means controlled by said second relay for applying current from said first mentioned source over said first line section, a chain of slow releasing relays initially controlled by said first mentioned relay, means controlled by said chain of relays for applying current from said second source to said second mentioned line section, and means controlled by said chain of relays for preventing current from said first mentioned source from being simultaneously applied to said first mentioned line section.

In testimony whereof, I have signed my name to this specification this thirteenth day of September, 1918.

JOHN F. TOOMEY.
